United States Patent Office.

JOHN A. GREEN, OF NORTH WATERFORD, MAINE.

Letters Patent No. 78,957, dated June 16, 1868.

IMPROVED HORSE-POWER.

The Schedule referred to in these Letters Patent and making part of the same.

TO ALL WHOM IT MAY CONCERN:

Be it known that I, JOHN A. GREEN, of North Waterford, in the county of Oxford, and State of Maine, have invented a new and useful Improved Horse-Power; and I hereby declare the following to be a full, clear, and exact description thereof, which will enable others to make and use my invention, reference being had to the accompanying drawings, forming part of this specification, in which—

Plate 1 shows a top plan.

Plate 2, Figure 1, a side elevation of the revolving post and opening and closing wheel.

Figure 2, a side view of the adjustable friction-pulley.

The purpose of my invention is the production of an improved horse-power for sawing and such like purposes.

A is any convenient base for the machine. B is the revolving post set on its pivot, *a*. This post has the head C, in which are sockets *b*. Set in and pivoted in these sockets are the arms *c*, which turn on their pivots up to a horizontal position, or can be turned down to rest against and around the post B, as indicated in fig. 1, plate 2.

These arms are further steadied by arms *d*, jointed to the arms *c*, and also to a sliding ring, *e*, which will slide upward and downward on the post, and allow the arms *c* to contract or expand, as indicated, the same being similar in operation to the arms or braces of an umbrella-top.

This is for convenience in carrying the said machine, as the arms *c* can then be lowered around the post B, and the whole occupy but little space, and still constitute a large wheel when expanded.

Around the periphery of the wheel thus constituted passes the cord *f*. The post B is braced by two diagonal horizontal arms *g g'*. These are notched on to two upright posts at *h*, and then on to the top, *i*, of the post B.

These braces *g g'* are removable, so that they can be easily packed with the other parts.

The cord *f* passes around the adjustable pulley *j*, and then twice around the shaft *k* at *l*.

This horizontal shaft is set in the two uprights *m m*. The method of rendering the pulley *j* adjustable is seen at *n* by the means of a stud and slot. Thus the tightness of the cord *f* is controlled around the arms *c* and the shaft *k*.

Upon the shaft *k* is the large wheel *o*, which has a band passing around it and the shaft *p*. On this shaft is set the saw *q*.

r is a bed with slots and studs *s*, to adjust it and the saw *q* and shaft *p* in relation to the wheel *o*.

t is a rod, in staples or other devices in the lower side of the braces *g g'*, and having at its end a truck, *u*, which plays against the cord *f*, so as to keep the two turns of it around the shaft *k* separate.

By drawing the rod toward *l*, the pulley will press against the cord *f* and keep the two turns around *k* separate. The posts *m m* can be removed, and also the bed *r*, by means of its slots and pins *s*.

Thus it will be seen that the whole machine can be taken down and packed up into a small compass, consisting of the post B, with the collapsible top or wheel, braces *g g'*, shaft *k*, posts *m m*, and bed and frame *r*, with the shaft *p* and saw *q*, and can be very easily set up again.

The operation of the machine is obvious, the revolution of the wheel made by arms *c*, carrying the belt *f*, revolves the shaft *k* and its wheel *o*, and this the shaft *p* and its saw *q* with great rapidity.

By the operation of the spring *x* the pulley *j* is rendered self-adjustable, being pressed outwardly, so as to tighten the cord or belt *f*.

What I claim as my invention, and desire to secure by Letters Patent, is—

1. The removable, portable, and collapsible wheel, composed of the arms *c*, set in sockets *b* on the post B, having ring *e* and arms *d*, all as and for the purposes set forth.
2. The combination of the said wheel, composed of arms *c*, with the shaft *k*, wheel *o*, and saw-shaft *p*, by means of cords or bands *f* and *v*, as herein set forth.
3. The adjustable pulleys or friction-rolls *j* and *u*, as and for the described purposes.
4. The combination, in the manner herein set forth, of the different parts described, in the manner and for the purpose of constituting a portable horse-power sawing-machine, capable of being taken apart and put together, as set forth.

JOHN A. GREEN.
